DENTAL EQUIPMENT STAND

Robert C. Angell, Prince Bay, N. Y., assignor to
The S. S. White Dental Manufacturing Company, a corporation of Pennsylvania

Original application April 5, 1939, Serial No. 266,174, now Patent No. 2,317,971, dated May 4, 1943. Divided and this application April 2, 1943, Serial No. 481,579

5 Claims. (Cl. 32—22)

This application constitutes a division from my copending application Serial No. 266,174, filed April 5, 1939, now Patent No. 2,317,971 dated May 4, 1943, and is specifically directed to spray bottle warmer and water tumbler supporting mechanism.

My invention relates particularly to that class of dental equipment assemblages that are adapted to be located adjacent to a dental operating chair and arranged to support, within easy reach of the operator, various instruments, implements, appliances and devices employed in the practice of dentistry, and is especially directed to its simplified construction, easy accessibility of its enclosed mechanism, wide range of relative movement of the associated parts, and the consequent flexibility in the use of such instruments.

The principal objects of my invention are to provide an assemblage of dental equipment devices embodied in stand or pedestal that is compact, pleasing in appearance, convenient to operate, readily assembled and taken apart and that affords a maximum degree of utility in the practice of the dental profession.

Other objects of my invention are to provide an equipment assemblage comprising a standard or pedestal upon which various relatively adjustable equipment and dental devices may be conveniently moved into relatively different operative positions about the common axis of said standard or pedestal.

Further objects of my invention are to provide a dental equipment stand assemblage in which the frame of the supporting standard is composed of a plurality of frame sections relatively superposed one upon another and secured together to form a supporting skeleton standard structure upon which the various equipment devices may be adjustably supported, and in which a shell or casing is formed of a plurality of casing sections having means cooperative with complementary means on said frame sections to cause said casing sections, when forced into their relative normal positions to closely embrace and enclose the assembled skeleton frame to form a pedestal structure or standard.

My invention further includes an equipment stand assemblage having a bracket table rotatably supported on a swingable supporting arm which is mounted for horizontal movement about the axis of said stand and including a frame carrying connection terminals for gas and air which are connected by flexible tubing spirally coiled about the common axis of said swingable

supporting arm and stand with suitably disposed stationary connecting terminals of gas and air conveying pipes extending upwardly through the stand or pedestal.

5 Another object of my invention is to provide a spray bottle warming unit and X-ray illuminator swivelingly mounted at the outer end of a swingable supporting arm which is in turn pivotally mounted on the bracket table arm and arranged to swing about the axis of the bracket table, whereby said spray bottle warming unit and X-ray illuminator are adjustable horizontally about three relatively spaced parallel axes.

My invention also embraces the electrical connection of relatively movable terminals and includes novel means for so guiding the interposed current conveying cord in such predetermined condition as to prevent its accidental displacement or entanglement when one terminal is 20 moved relative to the other.

Specifically stated, the form of my invention as hereinafter described, comprehends an equipment stand comprising a pedestal of generally cylindrical formation having a flanged base and 25 a dome-like upper extremity from which projects a cylindriform engine mechanism mounting, and having horizontally swingable arms disposed at relatively different levels and respectively carrying a bracket table and a cuspidor. 30 Said pedestal is preferably formed of a plurality of separable frame sections each designed to provide specifically for its intended purpose and assembled one upon another in a prescribed order and secured together with their respective 35 axes coincident with the axis of the thus assembled standard which provides a supporting frame standard that may be enclosed by a plurality of readily removable and replaceable substantially semicylindrical casing sections preferably of sheet 40 material assembled to form the cylindriform pedestal structure. The swingable arms for the bracket table and cuspidor are provided with suitably formed casing sections of sheet material which have their inner semicylindrical ends in 45 coincident alinement with the cylindrical wall formed by the adjacent casing sections and serve to form therewith the complete shell or closure for the above described assembled supporting standard, and providing the cylindriform pedestal 50 structure as illustrated.

My invention also includes all of the various novel features of construction and arrangement as hereinafter more definitely specified.

In the accompanying drawings, Figure 1 is a 55 fragmentary vertical sectional elevational view

of the equipment stand pedestal showing the base and upper portion with the intermediate region broken away for convenience of illustration, and including the inner end portion of the bracket table supporting arm; Fig. 2 is a plan view of said equipment stand pedestal including the bracket table, its supporting arm and embodying a secondary or forearm swingable horizontally about the axis of the bracket table and carrying at its free end a combined spray bottle warmer and X-ray illuminator rotatably mounted thereon, about a vertical axis at the free end thereof; Fig. 3 is a front elevational view of the structure shown in Fig. 2; Fig. 4 is a horizontal sectional view of the secondary or forearm which supports the spray bottle heater and illustrates the means for preventing entanglement of the electric cords leading therethrough to said spray bottle heater and X-ray illuminator when said arm is swung upon its axis of rotation; Fig. 5 is a fragmentary vertical sectional view taken through the electric cord directing guide on the line 5—5 in Fig. 4, a portion being shown in elevation for convenience of illustration; Fig. 6 is a perspective view of the electric cord directing guide which is shown in plan view in Fig. 4; Fig. 7 is a perspective view of the electric cord supporting guide to which said electric cord is attached and guided thereby into the spray bottle heater; Fig. 8 is a perspective view of the clip by which said electric cord is attached to said supporting guide; Fig. 9 is a front elevational view of the spray bottle heater and X-ray illuminator with a fragment of the swingable arm upon which they are mounted, a portion of the forward wall of said illuminator being broken away to better illustrate the interior parts; Fig. 10 is a transverse central vertical sectional view of the spray bottle heater and X-ray illuminator assembly, the upper portion of said spray bottle heater being shown in elevation for simplification; Fig. 11 is a fragmentary plan sectional view of the assembled structure shown in Fig. 10 taken on the line 11—11 in Fig. 10 and showing a fragment of the spray bottle heater frame; Fig. 12 is a side elevational view of the spray bottle, of which there are two shown in Fig. 9; Fig. 13 is a vertical longitudinal sectional view of the spray bottle heater shown in Figs. 2, 3 and 9 taken axially through the spray bottle receptacle; Fig. 14 is a plan view of the supporting frame of the spray bottle heater shown mounted for rotation upon a fragment of the outer end of the secondary or forearm of the bracket table arm; Fig. 15 is a horizontal sectional view of the spray bottle heater taken on the line 15—15 in Fig. 13; Fig. 16 is a transverse vertical sectional view taken axially through the water glass receptacle, the X-ray illuminator attached thereto being shown in elevation; Fig. 17 is an enlarged vertical transverse sectional view of the accessory bracket table arm brake and its cooperative brake ring shown in Fig. 1, taken on the line 17—17 in Fig. 2; and Fig. 18 is a perspective view of one of the similar opposed clamp blocks which retain the opposed friction brake pads, which are shown in Fig. 17.

In said figures the frame forming the supporting standard comprises the base section 1, the main body section 2, the combined water niche and cupid section 3, accessory table-arm section 4 and the dome or motor section 5, all being assembled by building one upon the other about a unitary common vertical axis in the order named to provide a skeleton standard structure upon which the various operating appliances, de-

vices and parts, to be hereinafter described, may be mounted for convenient utilization.

The base section 1 is provided with the enlarged base flange 6 adapted to rest upon the floor and to be secured thereto by the bolts 7 extended through suitably spaced apertures 8, and has four upwardly extending legs 9, terminating in a substantially octagonal perforated elevated plate or platform 10, said platform 10 being provided with two diametrically opposite outwardly projecting lugs 16 each having a vertical notch or slot 17 cut or otherwise formed therein, and indented for a purpose to be hereinafter described.

Superposed upon the base section 1 is the main body section 2 which comprises the relatively spaced parallel plane side walls 19 and 20 respectively terminating at their lower ends in the annular horizontally extended flange 21 and being joined vertically by the transverse wall 23 which is inset from the edges of said walls 19 and 20 but preferably disposed nearer to the rear edges of said walls.

The transverse wall 23 terminates short of the annular flange 21 and merges into the horizontally extended shelf 25 projecting rearwardly from the lower end of said transverse wall 23 and having its curved free edge joining the free vertically disposed rear edges of the side walls 19 and 20.

The main body section 2 is supported on the base section 1 and has the four feet 31 which depend from the under surface of the annular flange 21 in relatively spaced relation and rest upon the plate or platform 10 of base section 1 to which the main body section 2 is rigidly secured by the bolts 32, shown in Fig. 1.

The combined niche and cupid mounting section 3 is superposed upon the main body section 2 and comprises a unitary structure having the four posts or standards 40 terminating upwardly in the top plate or cap 41 unitary therewith and having a central aperture 42 and flange 43, and providing a circular horizontal track 44 and a cylindrical vertical track 45 for supporting bearing structure to be later described.

The accessory table-arm section 4 is superposed upon the water niche and cupid mounting section 3, and, as best shown in Fig. 1, comprises a hollow circular hub 54 having a depending inner rim bead 55 extending into a correspondingly formed recess or rabbet 56 in the cap 41 of the water niche and cupid mounting section 3 to which said section 4 is secured by bolts 57, one of which is shown in the plane of section in Fig. 1.

Said accessory table-arm section 4 is provided with the horizontal flange 58 disposed intermediate of its axial length and having a depending annular projection 59 providing a flat horizontal under surface affording a circular roller bearing track 60 in suitably opposed spaced relation to the circular track 44 on the cap 41. The upwardly extending portion of said hub 54 is externally recessed to provide the shoulder 61 arranged to support the annular shelf 62, and terminates upwardly in the inner rim bead 63.

The motor section 5 is superposed upon the accessory table-arm section 4 and serves as a crown-piece or dome for the skeleton standard structure thus assembled. Said motor section 5 comprises the annular floor 65 having the lower edge of its inner rim rabbeted to receive the upwardly extending inner rim projection or bead 63 on the circular hub 54, and to be secured thereto by the bolts 66, and from which floor 65 rise the diametrically opposite U-shaped standards 67 re-

spectively curving inwardly at their upper extremities and merging into the annular head 69.

The accessory table arm 70 is adapted to oscillately swing horizontally about the unitary axis of the standard structure upon which it is supported, and its frame 71 comprises at the free end an annular mounting 73 upon which an accessory table 72 may be conveniently supported, as shown in Figs. 2 and 3.

The inner end of the frame 71 comprises the circular bearing mounting 75, the rim of which embraces the hub 54 in concentric relation thereto and serves to provide a substantially annular inner terminal structure encircling said hub 54.

As best illustrated in Fig. 1, the table arm 70 is supported for horizontal movement into different positions convenient to the operator, by the three supporting rollers 87 respectively mounted on the headed trunnions 90, which project inwardly from the bearing mounting 75.

The rollers that serve best to directly carry the weight of the projecting arm 70 and the parts supported thereon, consequently are disposed relatively close to each other upon opposite sides of a vertical plane passing through the axes of the annular ends of the accessory supporting arm frame, and roll upon the track 44, while the roller 77 which serves to balance the arm 70 rolls upon the opposed superjacent track 60, and is preferably disposed with its axis of rotation substantially coincident with said vertical plane.

As shown in section in Fig. 1, the roller 77, which is typical of the three supporting rollers, is annular in form and is provided with a ball race 78 in its inner cylindrical surface, in opposed relation to the ball race 79 in the outward surface of the ball race annulus 80, and relatively revolves about said annulus on the bearing balls 81 which are arranged to traverse the opposed ball races 78 and 79.

In order to retain the accessory table arm 70 in axial registry with the supporting standard structure or pedestal, it is provided with the horizontally disposed equally spaced rollers 82 there being three such rollers arranged to traverse the cylindrical track 45, the roller 82, shown in the plane of section in Fig. 1, being disposed with its axis of rotation in a vertical plane coincident with the axis of the supporting roller 77 and journaled to rotate on the headed shaft 85 which, as shown in Fig. 1, extends through an aperture in the boss 86 on the inwardly projecting rib 87 of the bearing mounting 75, and which is engaged in stationary relation therewith by the nut 89 threaded thereon.

Thus it will be seen that the accessory table arm 70 may freely revolve about the axis of the standard structure and be moved into any desired position convenient to the operator. However, it has been found desirable to adjustably restrict its too free movement and to prevent its over running when its position is changed, and therefore a brake device is employed which, as shown in Fig. 17, comprises the annular disk 90 which is rotatably engaged between the water niche and cuspidor mounting section 3 and the accessory table arm section 4, and which is frictionally engaged between the jaws 91 and 92 of the brake device comprising the opposed jaw plates 93 and 94 respectively having the opposed lips or ridges 95 and 96 upon which they may slightly rock.

Said jaw plates are respectively provided with pockets 99 and 100 in which friction pads 101 and 102 are held in opposed relation in frictional engagement with the upper and under surfaces of said disk 90 respectively, said pads 101

and 102 being engaged with said disk in any desired degree of yielding frictional contact with said disk 90, see Fig. 17, by the adjusting screw 103, which extends through the aperture 105 in the jaw plate 94 and into threaded engagement with the jaw plate 93. Said adjusting screw 103 is encircled by the spiral spring 106 disposed between its head 107 and the jaw plate 94, and has the reduced end 109 extended into the aperture 110 in the accessory table arm section 4, whereby it is retained and prevented from radial displacement in the pocket 111 in the cap 41 of the water niche and cuspidor section 3.

The accessory table arm 70 is normally locked in engagement with said annular disk 90, so that it may be moved only by considerable manual pressure, the amount of which depending upon the frictional pressure of the friction pads 101 and 102 incident to the adjustment of said adjusting screw 103, but said arm may be automatically released from such locked engagement to freely move about its axis of rotation.

As shown best in Figs. 2 and 3, the hollow spray bottle warmer supporting arm 136, which is mounted to revolve about the axis of the accessory table 72 on the table mounting bearing 137, which is supported on the ledge 138 in the annular mounting 73 of the accessory table arm 70, as shown in Fig. 3, said arm 136 and table 72 being arranged to independently revolve upon the free end of said accessory table arm, and jointly movable about the axis of the supporting standard or pedestal.

As shown in Figs. 2, 3 and 9, said water warmer supporting arm 136 is provided at its free end with the annular mounting 140 upon which the spray bottle and water tumbler warmer 141 is mounted to revolve. Said warmer 141, as shown in Fig. 13 is provided with the receptacles 142, 143 and 144, respectively arranged to receive the removable and replaceable spray bottles 145 and 146 and the water tumbler 147, shown in Fig. 9, the spray bottle illustrated in side elevation in Fig. 12 being typical of both of those shown in Fig. 9, and comprising the connection nipple 148, the swivel coupling 149 and the nozzle 150.

The body 151 of the spray bottle and water tumbler warmer 141 is provided with the electric heating element 152 having the terminals 153 and 154 and secured thereto by the screws 155, see Fig. 13. Said body is mounted upon the base frame 156 from which it is insulated by the interposed diaphragm 157 of non-conducting material, and secured by the screws 160 extended through the lugs 158 of said base frame 156, said diaphragm 157 being independently attached to the lugs 159 of the body 151 by the screws 161.

The spray bottle warmer body 151, as shown in Figs. 13, 15 and 16, is provided with the shell or casing 162 between which and said body the jacket 165 of heat insulating material, preferably in sheet form, is interposed, and said shell or casing 162 extends downwardly and affords a depending apron which also embraces the base frame 156.

The spray bottle warmer is arranged to independently revolve on its supporting arm 136 which is provided at its outer free end with the inwardly extending rim 166 providing the bearing seat 167 upon which the centrally disposed generally circular spider 169 of the base frame 156 rests for relative rotation, being held in axial position thereon by the annular retainer 170 which rotatably bears against the under face of

the inset rabbet 171 in the inner edge of said rim 166, and said retainer 170 is secured to the frame spider 169 by the screws 172.

As shown in Figs. 13, 14 and 16, the base frame 156 is provided with the bottom closure supporting lugs 173 and 174 projecting inwardly and to which the bottom closure plates 175 and 176 may be secured by the screws 177 and 178 to enclose the chamber 179 included between said closure plates and said diaphragm 157, see Fig. 13.

The supply of electric current to the heating element 152 may be manually controlled to turn it on or off as may be desired, and it is also automatically controlled by thermostatically actuated mechanism to maintain a relatively uniform desired temperature.

Said electric current may be introduced into the spray bottle warmer by the electrical conductors 180 and 181 which lead from suitably provided connections and extend through the pedestal, accessory table arm and spray bottle arm 136, as shown in Figs. 14 and 16, and which extend spirally in the semicircular free end of said arm 136 and terminate at the terminals 182 and 183 in the terminal plates 184 and 185, on the terminal block of insulation material 186 which is secured to the spider frame 169 by the screws 187, see Fig. 14.

The electric circuit through the heating element 152 may be made or broken by mechanism including the rocker post 188 which extends vertically through the diaphragm 157 and which is mounted to rock in the bearing bracket 189 which, as shown in Fig. 15, is secured to the under side of said diaphragm 157 and secured by the screws 190 extended therethrough.

Referring again to Fig. 15, the rocker post 188 is provided beneath the diaphragm with the spring contact finger 191 which carries the contact 192 in opposed relation to the contact 193 mounted in stationary relation on the mounting bracket 194 also secured to the underside of said diaphragm 157 by the screw 195 extended therethrough, which mounting bracket 194 also carries the magnet 196 in opposed relation to the magnet keeper or bridge 197, which is carried by said contact finger 191 as above described.

With further reference to Fig. 15, the rocker post 188 is provided with the lever arm 198 which is connected by the link 199 to the outer end of the bimetallic thermostatic coiled spring or strip 200 which is limited in forward movement by the guide post 201 and is spirally coiled about the rock-shaft 202 journaled in the bearing bracket 203 secured to the underside of the diaphragm 157 by the screws 205.

Said rock-shaft 202, as shown in Fig. 16, carries at its lower end the hubbed disk 206 which is secured thereto by the screw 207, and which carries the rocker-arm or lever 209 having its inner circular end enlarged and encircling the hub of said disk 206 and secured thereto so as to move therewith by the screw 210. The outer circular end 212 of said lever 209 is extended into the rectangular void or recess 213, best shown in Fig. 13, in the rack-bar 215, having the upwardly projecting rack teeth 216.

With reference to Figs. 13, 15 and 16, the rack-bar 215 is arranged to slide longitudinally on the shelf type supporting bracket 217 which is secured to the diaphragm 157 by the screws 219 and depends therefrom, as shown in Figs. 13 and 16. Said bracket 217 has its lower horizontal wing or shelf 220, see Fig. 15, provided with the longitudinally extending apertures 221

and 222 through which the shanks of the screws 223 and 225, threadedly engaged in said rack-bar 215, extend with their respective heads 226 and 227 underlying and loosely engaging the under surface of said horizontal shelf 220 of the bracket 217, and maintaining the rack-bar 215 in sliding contact with the upper surface of said wing or shelf 220.

The teeth 216 of the rack-bar 215 are interengaged with the teeth of the pinion 230 on the inner end of the shaft 231 which is mounted to rotate in the bearing 232 depending from the diaphragm 157 and secured thereto by the screws 233. Said shaft 231 extends rearwardly through the casing 162 and is provided with the controlling knob 235 by which said shaft 231 may be rotated to shift the rack-bar 215 and thereby rotate the rock-shaft 202 to wind or unwind the coiled thermometal strip 200. A pointer 236 arranged to move with said knob 235 indicates the position of the rack-bar 215.

Turning of the controlling knob 235 in a clockwise direction effects winding up of the coiled strip 200 which tends to draw the lever arm 198 and the contact spring finger 191 toward the right hand with respect to Fig. 15 and to effect breaking of the electric contact between the contacts 192 and 193. Turning of the controlling knob 235 in an anticlockwise direction effects unwinding of the coiled strip 200 to produce movement of the contacts 192 and 193 together to complete the electric circuit therethrough to energize the heating element 152.

The coiled strip 200 is disposed in the chamber 239 with the heating element 152 and is arranged to automatically effect actuation of the lever arm 198 and the spring contact finger 191 to separate the contacts 192 and 193 and thereby break the electric circuit in which the heating element is included when the temperature in said chamber 239 rises to a degree predetermined by the position of said rack-bar 215 and variably controlled by the knob 235.

The terminal 153 of the heating element 152 may be connected through suitable wiring with the terminal 240 which connects through the contact finger 191, contacts 192 and 193 with the terminal 241 of the terminal plate 184. The terminal 154 of said heating element 152 may be connected through suitable wiring with the terminal 243 of the terminal plate 185. As above described, said terminal plates 184 and 185 are connected with the line wires 180 and 181.

As shown in Figs. 2, 3, 9, 10, 11 and 16, the X-ray illuminator 250 may also be carried by the spray bottle warmer arm 136 and is removably and replaceably attached to the forward side, as illustrated in Fig. 2 of said spray bottle warmer.

The frame 252 of said illuminator comprises the rearwardly extending support 253 resting upon the forward bar of the base frame 156 of the spray bottle warmer and is secured thereto by the screws 255 which extend upwardly through the countersunk apertures 256 in said base frame 156.

Said frame 252 supports the illuminator casting comprising the top wall 259, the bottom wall 260, both of which curvedly merge into the forward wall 262, and the end walls 263 and 265. Said forward wall 262 is provided with the window opening 266 which is surrounded by the window frame 267, the inner margin 269 of which overlaps said window opening 266, and is secured to said forward wall by the screws 270.

As shown in Figs. 9, 10 and 11, the window opening 266 is provided with the pane of glass 272 which is retained in the window opening 266 by the brackets 273 disposed oppositely and substantially in alignment with the lower edge of said glass pane 272 and respectively extending from the end walls 263 and 265 and provided with the outwardly projecting lugs 276 extending beneath the glass pane 272 and serving to support it, and the outwardly projecting lugs 277 which extend over the lateral edges of said glass pane to maintain it in proper registry with said window opening 266.

As shown in Fig. 10, the glass pane 272 is also retained by the brackets 279 similarly disposed oppositely in alignment with the upper edge thereof, said brackets 279 being similar to the brackets 273 and being provided with the outwardly projecting lugs 280 extending over the top edge of the glass pane 272 and the lugs 281 extending over the lateral edges of said glass pane.

As shown in Figs. 10 and 11, the brackets 273 and 279, which may preferably be secured by spot welding to the side walls 263 and 265 of the X-ray illuminator casing, are respectively provided with the spring clips 282, see Fig. 11, which are arranged to bear against the inner surface of the glass pane 272 to maintain it in the window opening 266 in contact with the inner overlapping margin of the window frame 267. The lower bar of the window frame 267 has the upturned extension 283 providing a convenient support for holding a film before the glass pane 272.

As shown in Figs. 9, 10 and 11, the X-ray illuminator is provided with the reflector comprising the complementary concave reflective sections 285 and 286 respectively having oppositely directed outwardly extended flanges 289 and 290, and the inwardly extended relatively parallel flanges 291 and 292. The flange 289 is engaged with the brackets 279 by the screws 293 and the flange 290 is secured to the brackets 273 by the screws 295, so that, as will be observed, the reflector comprising the complementary concave sections, forming a reflector structure having a substantially tangential parabolic contour, is supported by said brackets 273 and 279.

As best shown in Fig. 10, the flanges 291 and 292 of the reflector sections are secured to the bar 296 of insulation material, preferably "Bakelite" by the screws 297 to which bar the lamp supporting spring clip terminals 298 and 299 are attached by the screws 300 and 301 which extend through suitably provided apertures in said bar 296 in threaded engagement with the terminal plates 302 and 303 respectively.

The spring clip terminals 298 and 299 are conveniently spaced to receive the terminal collars 305 and 306 of the tube type electric lamp 307 which is provided with a backing of refractory material and which is supported by said spring clip terminals 298 and 299 in such predetermined relation to the parabolic reflector surface as to direct relatively parallel light rays through the glass pane 272.

The terminal plates 302 and 303 are provided with the screw terminals 309 and 310, the terminal 309 being connected by the electric wire 312 with the terminal 313 on the terminal plate 184 in the base of the spray bottle warmer, and the terminal 310 being connected by the electric wire 315 with the terminal 316 on the terminal plate 185 in the base of said spray bottle warmer. However, the wire 315 is connected through the rhe-

ostat switch 317 which is arranged to be actuated by the controlling knob 319.

As shown in Fig. 4, the wires 180 and 181 are included in the electric cord 320 which enters the spray bottle warmer supporting arm 136 through the tubular elbow fitting guide 322, and curves forwardly toward the free end of said arm into a free return loop 323 from which it extends rearwardly into the loop 325 permanently restricted by the clamp band 326, and from which loop 325 said cord 320 extends forward through the supporting and directing clip 327 from where it extends in the loop 329 upwardly through the bushing 330 in the free circular end 331 of the bushing supporting bracket 332 into the base 156 of the spray bottle warmer where said wires 180 and 181 are attached to their respective terminals, see Fig. 14.

Referring again to Fig. 4, the electric cord 320 rests upon the floor 333 which has that portion which is disposed between the elbow fitting guide 322 and the loop 323 backed by the guide 335 formed of a strip of sheet spring material that is secured in any manner, such as by the rivets 336, to the elbow fitting guides 322 and extends curvishly forwardly therefrom, forming a backing for said electric cord 320 and tending to prevent buckling thereof, and terminating in a preferably circular loop 337 arranged to slide upon the inner surface of the rear wall 339 of the spray bottle warmer arm 136.

With further reference to Fig. 4, it has been found desirable when the free end of the spray bottle warmer arm 136 is moved forwardly from its normal position with respect to the accessory table arm 170 and the electric cord 320 has been relatively shifted to the position shown in dot-and-dash lines in said figure, that the spring backing guide 335 be maintained flattened in its medial region, and for this reason the inwardly curved region of the rear wall 339 is provided with the elongated inwardly projecting abutment 340 against which said backing guide may rest, as illustrated.

As shown in Fig. 5, the depending portion 342 of the elbow 322 extends into the sleeve 343 which is supported by the flange 345 resting upon the ledge 346, and said sleeve 343 is restricted at its lower end to provide a bearing 347 for said elbow 322, and said restricted end portion is provided with screw threads 349 with which the nut 350 is threadedly engaged.

As illustrated in Fig. 7, the bracket 332, which is shown in perspective therein, has its inner end portion 352 slightly depressed and terminates in the enlarged circular attachment 353 having the aperture 355 through which the screw 356 extends, see Fig. 4, to engage it with the lug 357 extending inwardly from the forward wall 360 of the spray bottle warmer supporting arm 136. Said screw 356 also engages the clip 327 which, as shown in Fig. 8, has the circular attachment 362 provided with the aperture 363 through which said screw extends to attach it in superposed relation to the attachment 353 of the bracket 332.

Referring to Fig. 4, it will be obvious that the spring backing strip 335 tends to maintain the electric cord 320 in such curved relation, irrespective of the position of the spray bottle warmer arm with respect to the accessory table supporting arm upon which it is arranged to revolve, and that when said electric cord 320 moves from its retracted position, shown in dot-and-dash lines, to its extended position, shown in full lines, it will

be so reinforced and supported as to prevent its buckling or fouling, or otherwise tending to jam and interfere with the free movement of said spray bottle warmer arm.

My invention has many advantages over similar devices as heretofore constructed for supporting parts and accessories in convenient position for use by the professional operator, and affords not only easy access for use, but facilitates access for adjustment, repairs and replacement of all of said parts, and is particularly adapted for eliminating parts that may not be desired by individual operators and the substitution or addition of parts and accessories that may be desired, by other operators, and, in this particular respect, it is possessed of individual flexibility and consequent superiority.

I do not desire to limit my invention to the precise details of construction and arrangement as herein set forth, as it is obvious that various modifications may be made therein without departing from the essential features of my invention as defined in the appended claims.

Having thus described my invention, I claim:

1. A dental equipment assemblage comprising a supporting standard, a relatively movable supporting frame providing a radially extended arm arranged to swing about the axis of said standard as a center, an accessory table supported on said arm and arranged to independently rotate thereon, a secondary supporting arm mounted on the table supporting arm and movable horizontally about the axis of said table, an accessory device mounted for independent rotation on the free end of said secondary arm, and including electrically energized elements connected with a source of electric energy by an electric conductor extending through said supporting arms and having a free loop and a cooperative restricted loop whereby to facilitate extension and retraction of said conductor, and a spring backing guide arranged to maintain said looped conductor properly posed.

2. An equipment assemblage comprising a mounting, a hollow supporting arm mounted on said mounting arranged to swing on a vertical axis and having a floor provided with an opening and marginal walls embracing said floor, a conductor entering said arm through its supported end region and leaving said arm at its free end region and including intermediate loops preferably resting on said floor and slideable thereon to afford extension and contraction incident to variation of the distances between the entrance and exit points of said conductor, and a spring back-

ing guide arranged to maintain said conductor properly posed to prevent its fouling when said arm is swung on its mounting.

3. An equipment assemblage comprising a mounting, a hollow supporting arm mounted on said mounting arranged to swing on a vertical axis and having a floor provided with an opening and marginal walls embracing said floor and having an internal abutment; a conductor entering said arm through its supported end region and leaving said arm at its free end region and including intermediate loops preferably resting on said floor and slideable thereon to afford extension and contraction incident to variation of the distance between the entrance and exit points of said conductor; and a spring backing guide limited in its movement by said abutment and arranged to maintain said conductor properly posed to prevent its fouling when said arm is swung on its mounting.

4. An equipment assemblage comprising a mounting, a hollow supporting arm mounted on said mounting arranged to swing on a vertical axis and having a floor provided with an opening and marginal walls embracing said floor, a conductor entering said arm through its supported end region and leaving said arm at its free end region, and including intermediate loops preferably resting on said floor and slideable thereon to afford extension and contraction incident to variation of the distance between the entrance and exit points of said conductor; and a spring backing guide provided with a curved bight serving as a slide shoe, arranged to maintain said conductor properly posed to prevent its fouling when said arm is swung on its mounting.

5. An equipment assemblage comprising a mounting, a hollow supporting arm mounted on said mounting arranged to swing on a vertical axis and having a floor provided with an opening and marginal walls embracing said floor; a conductor entering said arm through its supported end region and leaving said arm at its free end region and including intermediate loops preferably resting on said floor and slideable thereon to afford extension and contraction incident to variation of the distance between the entrance and exit points of said conductor; and a spring backing guide anchored at its inner end and provided with a curved bight at its free end serving as a slide shoe arranged to maintain said conductor properly posed to prevent its fouling when said arm is swung on its mounting.

ROBERT C. ANGELL.
